MARKING MACHINE

Carl Putnam, Norristown, Pa.

Application May 6, 1941, Serial No. 392,156

1 Claim. (Cl. 101—309)

This invention relates to improvements in marking machines of a type adapted more particularly for marking hosiery.

Heretofore it has been customary to mark hosiery by means of decalcomania or transfers. This method is relatively slow and expensive, and particularly so by reason of the more recent requirement for multiple marking at the toe, heel, and instep, and sometimes also on the welt.

The principal object of the present invention is to provide a relatively simple and efficient machine for marking hosiery with the required multiple marks, the machine being characterized by a high degree of flexibility in adjustment in order to accommodate the markings to different sizes, characters, and colors of hosiery.

The invention resides further in certain structural and mechanical details which function jointly to afford a machine of the stated characteristics.

In the attached drawings:

Figure 1 is a side elevational view of a machine made in accordance with the invention;

Fig. 2 is a front elevational view of the machine;

Fig. 3 is a vertical sectional view on the line 3—3, Fig. 2;

Fig. 4 is a horizontal sectional view on the line 4—4, Fig. 1;

Fig. 5 is a vertical sectional view on the line 5—5, Fig. 1;

Fig. 6 is an enlarged fragmentary plan view on the line 6—6, Fig. 1;

Fig. 7 is an enlarged bottom plan view of one of the marking elements detached from the machine;

Fig. 8 is a section on the line 8—8, Fig. 7;

Fig. 9 is a detached view in perspective of one of the color pots constituting an element of the marking mechanism;

Fig. 10 is a fragmentary side elevational view illustrating a safety device forming a desirable feature of the machine, and

Fig. 11 is a section on the line 11—11, Fig. 10.

The machine comprises a fixed frame 1, which may be of the general form shown in the several drawings. Mounted on the rear of the frame is a motor 2 which constitutes the prime mover of the machine, and this motor is connected, through a suitable reduction gear 3, pulleys 4 and 5, belt 6, and clutch 7, with a shaft 8 which is journaled in and extends transversely of the frame 1. The clutch 7 is, preferably, of the single revolution type which, after engagement, will disengage automatically after one full revolution of the shaft 8. In the present instance, the clutch 7 is engaged by means of a treadle 9 at the forward end of the machine, which treadle is operatively connected to a rock shaft 11 extending to the rear of the machine, as best shown in Fig. 3, this shaft having at its rear end an arm 12 which is

connected through a link 13 with one arm 14 of a pivoted bell crank lever, the other arm 15 of this lever being suitably connected with the movable element 7a of the clutch 7. A spring 16, secured to the arm 15 and to the frame 1 of the machine, exerts resilient pressure tending to retain the element 7a in the disengaged position.

The shaft 8 carries an eccentric cam 17 which is confined between a pair of rollers 18 and 19 on a reciprocating member 21. This member 21 comprises two longitudinally extending side members 22, 22 which lie respectively at opposite sides of the cam 17 and are longitudinally slotted, as indicated at 23 in Fig. 3, for reception of the shaft 8. The rollers 18 and 19 are pivotally supported on pins 24, 24 extending between the arms 22, 22. The rear end of the member 21 is, therefore, supported by the shaft 8, with the rollers 18 and 19 in engagement with the cam 17. The forward end of the member 21 is pivotally connected at 25 with a lever 26, this lever being pivotally supported on the frame through the medium of a transverse shaft 27. The upper end of the lever 26 is connected, through a link 28, with a cross-head 29 which is slidably supported in guides 31, 31 in a rocker 32 pivotally suspended on a transverse shaft 33 in the top of the frame 1. Oscillation of the lever 26, through the medium of the member 21 and cam 17, will effect a reciprocation of the cross-head 29 in the rocker 32.

The shaft 8 also carries a pair of cams 34, 34 positioned at opposite sides of the cam 17, and each of the cams 34 is engaged by a lever 35 pivotally supported on a shaft 36 extending transversely of the frame 1. The other end of each of the levers 35 is connected, through a rod 37, with the rear end of the rocker 32. It will be apparent that oscillation of the levers 35, through the cams 34, will result in an oscillation of the rocker 32 about its supporting shaft 33. Projecting over the rear end of the rocker 32 is a bracket 38 on the frame 1, and springs 39, 39 are confined between the rear end of the rocker 32 and the overlying bracket 38 and exert resilient pressure to maintain the levers 35 in engagement with the surfaces of the cams 34.

Depending from the forward end of the cross-head 29 is an arm 41 which has at its lower end a transversely extending beam 42. Secured to the beam 42 by means, in the present instance, of bolts 43 are a plurality of brackets 44, these brackets being three in number in the present instance, and being illustrated in Figs. 7 and 8. As therein shown, each of the brackets 44 comprises an arm 45 which is provided with a longitudinal slot 46 through which the securing bolts 43 extend and which provide for adjustment of the brackets on the supporting beam 42. At the forward end of the arm 45 is a depending boss 47, in which is slidably supported the stem 48 of a marking die 49. The stem 48 is retained in the

boss by a collar 51 which is secured by a set screw 52 to the upper end of the stem and which seats upon the upper end of the boss 47. The boss is countersunk at the bottom for reception of a spring 53 which exerts resilient pressure against the die 49, tending to hold the latter in a depressed position in the boss and causing the retaining collar 51 to seat solidly upon the upper surface of the boss. Preferably the opposed surfaces of the boss and the collar 51 are toothed, as indicated at 54, so as to prevent the die 49 and the stem 48 from turning in the boss, this toothed engagement also providing for adjustment of the die in the bracket about the axis of the stem 48.

Supported on brackets 55, 55 at the forward end of the frame 1 is a table 56 which extends transversely of the machine. This table is formed, as best shown in Fig. 6, with a central relatively fixed top section 57, and at each side thereof a relatively movable section 58, these latter sections being supported at the edges in dovetailed guides 59, and being slidably adjustable longitudinally of the table 56 and with respect to the central section 57. The relatively movable sections 58 are engaged at the under side by a right and left-hand adjusting screw 61, which is rotatably supported in the table 56 and which may be operated through a hand wheel 62 to adjust the movable sections 58 of the table top toward and from the central section 57.

The table 56 is adapted to support the article to be marked, as indicated in broken lines in Figs. 4 and 6, and the table top sections 57 and 58 are adapted to cooperate as platens with the dies 49 in the marking operation. Thus when the table sections 58 are adjusted to accommodate an article of given size, the die brackets 44 will be correspondingly adjusted on the beam 42 to bring the dies into alignment respectively with the table top sections. This adjustment of the brackets 44 on the beam is effected in part through the medium of the slots 46 of the brackets 44 and, longitudinally of the beam, through the medium of slots 63 in the beam, see Fig. 4, through which the securing bolts 43 extend. It will be apparent that the slots 63 of the beam and the slots 46 of the die brackets 44 afford the latter a substantially universal adjustment with respect to the table 56. It will be noted by reference to Fig. 6 that scales 64 are provided on the table 56 to provide for rapid and accurate adjustment of the movable sections 58 of the table top in accordance with the particular size of the article to be marked.

It will be apparent that the platen top of the table 56 may be made in one piece of adequate dimensions. It is desirable, however, that the end edges of the table be unobstructed so as to permit the operator to draw the ends of the article to be marked downwardly over the edges, as shown in the drawings, thereby stretching the article flatly on the platen and at the same time removing the hands of the operator from the areas of the dies. When used in this manner, the free edges of the table act as templates to enable the operator to locate the articles accurately on the platen for uniform marking. By making the table top adjustable as to effective length, advantage of this desirable feature may be had for articles of all different sizes within the capacity of the machine.

On the main frame 1 at the rear of the table

56 is a sub-frame 65 which extends transversely of the machine and constitutes a support for a plurality of color or ink pots 66. One of these ink pots is illustrated in Fig. 9. The pot consists 5 of an open-topped receptacle 67 within which is rotatably supported a roller 68. One of the trunnions of this roller extends through the side of the receptacle and carries a gear wheel 69, and this wheel meshes with a pinion 71 which 10 is journaled on a stud 72. At the forward end of the pot is a transverse lip 73, and at the rear end is an extension 74. Pivotedly secured at 75 to the extension 74 is a clamping element 76 which carries a clamping screw 77. In assembly 15 and as shown in Figs. 3 and 6, the lip 73 fits slidably in a slotted recess formed in the rearward face of an upstanding flange 78 of the sub-frame 65, and the extension 74 seats upon a 20 horizontal flange 79 at the rear side of the sub-frame 65. The clamping element 76 is adapted to embrace the rearward edge of the flange 79, and the screw 77 when tightened against the under side of the said flange clamps the pot securely in position in the sub-frame.

25 Journaled in the sub-frame and extending continuously over the transverse length of the frame is an elongated gear 81 which, when the pot is clamped in position as described above, meshes with the pinion 71 on the color pot. A transverse 30 shaft 82 is journaled in the sub-frame 65 below the gear 81, and secured to this shaft is a gear 83 which meshes with the gear 81. The shaft also carries a ratchet wheel 84 which is engaged by a pawl 85 pivotally secured to an arm 86 journaled loosely on the shaft 82. The outer end of the arm 86 is connected, through a rod 87, with the lever 28. Oscillation of the lever 28 thereby effects, through the medium of the ratchet 84 and gear 83, an intermittent rotation of the gear 81, and through this gear, the pinion 71, and the gear 89, a corresponding intermittent rotation of the roller 68 in the color pot. It will be apparent that by release of the clamping screw 77, the pots may be readily adjusted to various positions longitudinally of the sub-frame 65 and of the machine, or may be quickly removed from the sub-frame 65 for replacement by pots containing other color mediums. The pots 66 are three in number and are adapted to cooperate with the respective die 35 40 45 50 55 elements to supply coloring medium to the faces of the dies. To this end, the pots are adjusted on the sub-frame 65 into alignment with the respective dies and with the several top sections of the table 56 with which the dies cooperate, as previously set forth.

The mode of operation is as follows: When the machine is put into operation, the cross-head 29 will be given a reciprocatory movement in the guide 31, thereby effecting a corresponding reciprocation of the several marking dies. Due to the action of the cams 34 in oscillating the rocker 32, the movement of the dies will not be rectilinear, but will follow an irregular path which will bring the die into contact both with the article 60 to be marked, which is located on the table 56, and also with the ink or color roll 68 of the associated color pot. In Fig. 3, the marking die is shown in the advanced and forwardly depressed position in which it is in printing engagement with the article supported by the operator upon the table 56. In this position, the lever 28 is at the forward end of its oscillation and the rocker 32 also is in the extreme position of oscillation, wherein the forward end of the rocker is depressed to a maximum extent. It will be noted

that by reason of the resilient mounting of the marking die 49 in the supporting bracket 44, the contact of the die with the article is a resilient one, the pressure of contact being determined by the pressure exerted by the spring 53.

The cam 17 is formed so that there will be a slight dwell in the cross-head in this advanced position. The cams continuing to rotate, the levers 35 will be immediately released from the high points 34a of the cams 34, with the result that the rear end of the rocker 32 will be depressed under action of the springs 39, thereby elevating the several marking dies from the now marked article to a position of maximum elevation wherein, as the cam 17 operates to retract the cross-head 29, the dies will move in elevated paths clearing the tops of the ink rolls 68. At or near the point of maximum retraction of the cross-head 29, the cams 34, by reason of the elevations 34b, will depress the forward end of the rocker 32 to the position shown in Fig. 1, wherein as the cross-head 29 is advanced, the die elements will be brought into facial engagement with the peripheries of the ink rollers 68 of the respective pots. When intaglio dies are employed, the conventional doctor blade (not shown) will be provided to scrape the excess ink from the face of the die after the latter has contacted the ink roller.

After the forward movement of the cross-head has progressed to the point where the dies are in position above the table 56, the high points 34a of the cams 34 will again act to depress the forward end of the rocker 32, thereby carrying the dies downwardly into contact with the article placed by the operator upon the table 56. This cycle of operations will be repeated, and the action will be an intermittent one or will be continuous, depending on the choice of the operator. Thus, if the operator in starting the machine depresses the treadle 9 and immediately releases it, the machine will pass through one complete cycle of operations, and will stop when the cross-head is in the retracted position, this by reason of the action of the single revolution clutch previously described. If the operator maintains the treadle 9 in the depressed position, the cycle of operations will be continuous.

In the present instance, when the dies are in the forward depressed or marking position, the rocker 32, and also the working faces of the dies, are slightly inclined to the horizontal, see Fig. 3. Correspondingly, the top surfaces of the platens 57 and 58 are inclined upwardly toward the rear edges. This arrangement affords better visibility for the operator and aids in placing the articles to be marked accurately and flatly on the platens. It will be apparent that by simple rearrangement of the parts in the assembly, the dies can be made to engage the platens in a horizontal plane if for any reason that might be found desirable.

In Figs. 10 and 11, I have illustrated a safety device which will preclude injury to the fingers of the operator if inadvertently caught beneath the marking dies as the latter move downwardly toward the platen. The levers 35a, which correspond to the levers 35 described above, are in this instance provided with a pivoted end section 88 which carries the roller 89 engaging the cam 34. This end section, which is pivoted at 91 to the body of the lever 35a, is normally held in proper position with respect to said body by means of a spring 92, this spring being confined between a flange 93 on an extension 94 of the pivoted end section 88 and an opposed flange 95 on the body of the lever. The pressure of

the spring 92 is sufficiently great to offset the pressure of the springs 39 previously described, but is sufficiently light to permit the end section 88 of the lever to turn angularly around the pivot 91 in the event that the hand of the operator offers an obstruction to the normal approach of the dies to the platen.

It will be noted that the machine is adapted to mark the feet of hosiery at three separate points, namely, at the toe, at the heel, and at the instep. Adjustment of the elements of the machine for marking hose of different sizes may be rapidly and efficiently effected through the medium, first of the adjusting screw 62 on the table, a corresponding adjustment of the brackets 44 on the beam 42, and a similar adjustment of the color pots 66 on the sub-frame 65. The design of the mechanism, as described above, also provides for rapid removal of the color pots 65 from the supporting frame for substitution of pots containing other colors or characters of ink or color medium.

One of the advantages of a machine of this character in the marking of hosiery over the prior transfer or decalcomania method resides in the greater latitude which it affords in the data content of the individual markings. To include in the marking with the standard data items of size, and name of producer or merchandizer, such additional items as character of material and color, would require the maintenance of a prohibitively large and various stock of decalcomanias; whereas it is entirely practical to maintain the required variety of marking die each inclusive of all these items. It will be understood, however, that the machine is not limited in its utility to the marking of hosiery, nor to the use of multiple dies, since for the marking of certain products a single die may suffice.

I claim:

In a marking machine comprising a work supporting platen, marking means coacting with the platen and movable in vertical planes to and from the latter, and means for supplying ink to the marking means; said marking means comprising a carrier and a plurality of separate marking dies mounted and individually adjustable on the carrier in directions both parallel to and transversely of said planes of movement so as to provide for varying the relative positions of the dies both longitudinally and laterally of the working face of the platen; said inking means comprising a support structure parallel to the platen, a plurality of receptacles slidably mounted in said support structure for individual adjustment transversely of said planes of movement and longitudinally of the platen, an applicator roll in each receptacle and an external gear for rotating the roll, an elongated gear in said support structure extending transversely of said planes of movement for operative connection through the first named gears with the said applicator rolls, said elongated gear providing for operation of said rolls in any of the said adjusted positions of the receptacles in the said structure; and mechanism for driving the said elongated gear and for simultaneously actuating the said carrier so as to move the dies in said vertical planes and into engagement successively with the platen and the applicator rolls of the respective receptacles.

CARL PUTNAM.
